UNITED STATES PATENT OFFICE.

HERBERT C. ROUTERY, OF LOS ANGELES, CALIFORNIA.

ONE-PIECE GARMENT.

1,072,776.

Specification of Letters Patent.

Patented Sept. 9, 1913.

Application filed August 8, 1911. Serial No. 643,043.

To all whom it may concern:

Be it known that I, HERBERT C. ROUTERY, a subject of Great Britain, having declared my intention of becoming a citizen of the 5 United States, residing at Los Angeles, in the county of Los Angeles and State of California, have invented a new and useful One-Piece Garment, of which the following is a specification.

10 An object of this invention is to provide a one-piece garment adapted for various uses, among which may be mentioned bathing or athletic suits for men and boys for wear where rigid requirements of decorum 15 in dress are exacted.

Another object is to produce a combined upper and nether garment of neat and attractive appearance and minimum weight. Also to provide a unitary garment giving 20 the appearance of a coat and vest which can be put on and taken off with great ease, which is adjustable to a large variation of size by a minimum amount of adjustment, and which will allow the coat to be freely 25 open in front without exposing the person of the wearer.

A special object of the invention is to avoid double thickness of cloth where practical, and to allow the body of the wearer 30 maximum freedom of movement.

The accompanying drawings illustrate the invention.

Figure 1 is a front view of the garment open ready to be donned. Fig. 2 is a view 35 of the same garment as it appears buttoned on the wearer when the coat is open. Fig. 3 is a view of the same garment completely closed and buttoned on the wearer. Fig. 4 is a section on the medial plane of the garment as shown in Fig. 3, the thickness of the 40 material being exaggerated for clearness of illustration. Fig. 5 is a fragmental detail illustrating an elastic construction.

The garment comprises a coat portion 1 and a trousers portion 2. The coat portion 1 comprises the usual back 3, front laps 4, 5, with arm holes 6 and sleeves 7, said coat being provided below the waist line 8 with the usual tail 9 and preferably being constructed as a Norfolk jacket. Said coat portion 50 also preferably has a shawl collar 10 that can be turned up to protect the neck.

The trousers portion terminates at the 55 bottom in the legs 11 which may be of any suitable length and are shown as being cut

off just above the knee and below the tail. Said trousers portion comprises a seat and hip portion 12 at the back of the trousers and reaching to the waist line and joined by any suitable means as by the stitches 13 to the inside of the coat back at the waist line and above the tail portion; thus allowing the tail portion to swing loosely, thereby maintaining the appearance of a two-piece garment. The front of the trousers terminates in a bib 14 reaching above the waist-line to the breast line just below the neck and extending from side to side of the garment. The seat and hip portion 12 is separated for a distance down from its top 60 from the bib 14 so that above the legs the trousers are formed on each side with an open gap between said portions 12 and 14, thus allowing lateral freedom to the body of the wearer.

75 Tabs 15 are attached to the inside of the front laps of the coat in front of the arm holes, and the bib 14 and the tabs 15 are provided with fastening means as the buttons 16 and the button holes 17, at the level of the shoulders by which to connect the bib and laps. The laps are also provided with suitable fastening means as the buttons 18 and button holes 19 by which they are fastened together over the bib after the bib 80 has been fastened to the tabs.

85 Ornamental trimming straps 20 may be applied at both front and back, the front trimming straps being on the front of the flaps opposite the tabs.

90 A belt 21 provided with button and button holes 22, 23, may be provided as with the usual Norfolk jacket.

95 For bathing and athletic suits it is deemed preferable to cut the arm holes and fit the sleeves large and loose as with an ordinary shirt; and the sleeves 7 are short so as to give freedom to the arms.

If desired the trousers may be attached 100 to the coat section by an elastic connection as suggested by the elastic straps 25 as shown in Fig. 5, thus making the garment adaptable to a greater range of sizes and also minimizing any tendency on the part of the coat and trousers to rip or tear apart.

105 In practical use to don the garment it will be opened as shown in Fig. 1 and will be drawn up over the legs and then the arms will be put through the sleeves and the bib drawn up into position and buttoned to the 110

tabs. The front laps will then be lappel and buttoned and the belt buttoned and the garment is ready for use.

Series of button holes 17 are shown in the 5 tabs through which the buttons 16 may be alternatively buttoned, thus to loosen or tighten the bib to fit the wearer both as to height and width; said button holes being stationed at different distances from arm 10 hole and waist so that the breast or bust measure and length can be changed at will. By means of the tabs and the fasteners 16 and 17 the bib is fastened to the laps without inconvenience and in a concealed manner. 15 The buttons 16 are preferably on the outside of the bib so as to be away from the body of the wearer.

I claim:—

1. A garment comprising a coat portion 20 having a tail and laps and a trousers portion having a front bib, the back of the trousers portion being fastened to the back of the coat portion at the waist line, and fastening means by which the bib may be fastened 25 to the laps at the breast line.

2. A garment comprising a coat portion having laps at the front, a trousers portion fastened at the back to the coat portion and provided at the front with a bib extending 30 from side to side of the garment, means to fasten the bib to the coat portion at the breast line and means to fasten the laps over the bib.

3. A garment comprising a coat portion 35 and a trousers portion fastened together at the back, a bib extending from side to side of the garment at the front of the trousers portion and means to fasten the bib to the coat portion at the breast line, said coat por-

tion being provided with laps to cover the 40 bib.

4. A garment comprising a coat portion having laps in front, tabs at the breast line on the inside of the laps; a trousers portion fastened at the back to the back of the coat 45 and provided at the front with a bib extending to the breast line and means for detachably fastening the bib and the tabs together.

5. A coat provided with tabs on its inner 50 side, said tabs being provided with button holes spaced apart to allow adjustment of size, and trousers fastened to the coat and provided with a front bib and buttons on the bib to engage said button holes. 55

6. A coat and a pair of trousers; the trousers being cut off at the knee, the fore part of the trousers being formed with a bib extended above the waist line up to near the level of the breast line, there being tabs 60 on the coat, the bib being provided at the top outside edges with fastening devices adapted to engage the tabs on the inner side of the coat, and means fastening the backs of the coat and trousers together. 65

7. A garment comprising a coat and trousers, elastic connection between the coat and trousers at the back thereof and a bib extending up at the front of the trousers and connected with the coat above the waist line. 70

In testimony whereof, I have hereunto set my hand at Los Angeles, California, this 3d day of August, 1911.

HERBERT C. ROUTERY.
